CLAIM

I claim the ornamental design for a removable organizer liner for handbag, as shown and described.

DESCRIPTION

FIG. 1 is a perspective view of a removable organizer liner for handbag showing my new design, shown in its environmental use;

FIG. 2 is a top plan view thereof;

FIG. 3 is a front perspective view thereof;

FIG. 4 is a front plan view thereof, the rear plan view being an identical image thereof;

FIG. 5 is a left side plan view thereof, the right side plan view being an identical image thereof;

FIG. 6 is a bottom plan view thereof;

FIG. 7 is a cutaway, front perspective view thereof; and,

FIG. 8 is a cutaway, rear perspective view thereof.

The broken line showing of a handbag is for illustrative purpose only and forms no part of the claim.
